UNITED STATES PATENT OFFICE.

FRANK H. KNIGHT, OF LANCASTER, PENNSYLVANIA, ASSIGNOR OF ONE-HALF TO
W. B. RUSH, OF LANCASTER, PENNSYLVANIA.

AUXILIARY INFANT'S SEAT.

1,147,328.

Specification of Letters Patent. Patented July 20, 1915.

Application filed January 16, 1915. Serial No. 2,545.

To all whom it may concern:

Be it known that I, FRANK H. KNIGHT, a citizen of the United States, residing at Lancaster, in the county of Lancaster and 5 State of Pennsylvania, have invented certain new and useful Improvements in Auxiliary Infants' Seats, of which the following is a specification.

This invention relates to auxiliary 10 detachable infants' seats for water-closets, commodes and the like, the objects being to provide such a seat with a folding rest in which the infant may be strapped and which may be folded very compactly for 15 shipping and storage, thus guarding against breakage or damage during transit, and to further provide detachable means for quickly and securely attaching the same to the usual seat of any thickness, said objects 20 being accomplished by the construction, combination and arrangement of parts all as hereinafter more particularly set forth and claimed.

In the accompanying drawings: Figure 1 25 represents a side elevation of a device embodying my invention as attached to a closet seat, the latter and the bowl being indicated in dotted lines; Fig. 2, a vertical longitudinal central section through the same, the 30 rod and clamping elements being shown in side elevation and the permanent seat B being indicated in dotted lines as clamped between seat 3 and the clamping strap 10 and plate 13; Fig. 3, a top plan view of the seat, 35 rest and clamping elements in their folded position; and Fig. 4, a vertical central longitudinal section on line 4-4 of Fig. 3.

Referring now in detail to the drawings, A indicates the bowl and B the permanent 40 hinged seat, both being of any usual construction as indicated in dotted lines in Fig. 1.

1 indicates the bottom of the auxiliary seat having the usual small opening 2 and 45 provided with a slot 3 running longitudinally of bottom of seat 1 from the center of the rear edge thereof. Front arms 4, connected at their upper ends to the U-shaped rest 5 by pivots 6 near the ends thereof, are 50 connected by pivots 7 to angle pieces or brackets 8 secured to the bottom of seat 1 by screws 9, said brackets 8 being arranged on a line at right angles to the longitudinal central line of the bottom of seat 1 and near 55 the front of the latter.

To the underface of seat 1, and in line with and swinging through slot 3, is the clamping member or strap 10 pivotally connected to a little bracket, lug or fitting 11 by a pivot 12, the said lug 11 being fastened 60 by any suitable means to the underface of said seat 1. This strap 10 is provided with an integral clamping plate 13 on its outer end and has a longitudinal slot 14 between its pivot 12 and said plate 13. Also, said 65 strap 10 is made of resilient metal or other suitable resilient material and is bent upward at an angle of about 45 degrees at a point about one third of its length away from its pivotal point 12, so that when portion *a* of said strap 10 lies flat against the underface of seat 1 the portion *b* will protrude through slot 3 with the plate 13 well above the upper surface of seat 1, as shown in Fig. 4, and when the strap 10 is swung 70 down so that the portion *a* is at an angle of about 45 degrees to the lower face of said seat 1 the portion *b* and plate 13 will lie parallel to said seat 1, as shown in Fig. 2.

A bar or rod 15, fulcrumed on rod 16 80 mounted in bracket 17 secured to the upper face of seat 1, is pivotally connected to lug 18 riveted to the center of the back of rest 5 and has its lower end protruding through slot 14 in strap 10, bent forward at a slight 85 angle and screw-threaded near its end to receive a winged nut 19 which bears against the under surface of portion *a* of the strap 10, see Fig. 2, thus obtaining the full benefit 90 of the resiliency of the strap 10 as well as the compressing action of the nut 19 in the clamping operation. Bending the end of rod 15 forward deflects it out of the way of the inner edge of the permanent seat B when set up, also it allows the rest 5 to fold 95 down flat while using a shorter strap 10 provided with a slot 14 than would be the case were the rod 15 perfectly straight, as will be obvious from the drawings.

A restraining strap 20 may be provided 100 to connect the end of rest 5 by snap hooks, or in any other suitable or usual manner.

In operation, to attach the seat 1, the rest 5 is first swung to its highest position. The auxiliary seat 1 is then slid on the usual permanent seat B with the part of seat 1 adjacent slot 3 engaging the upper face of seat B and the clamping plate 13 in line therewith and underneath the lower face of the seat B. The nut 19 is then screwed up on 110

the rod, forcing the strap 10 to swing upward on its pivot until the clamping plate 13 is forced tightly against the under face of the seat B, which is then tightly clamped 5 between the under face of seat 1 and the upper face of plate 13. The infant may then be placed on the seat 1 and fastened in rest 5 by strap 20. To detach it suffices to loosen the nut 19 by giving it a half turn 10 and then withdraw the seat 1.

To fold the rest 5, seat 1 and clamping elements to their most compact form the rest 5 is to be pushed forward and downward until it lies perfectly flat and parallel with 15 seat 1, with its ends and the arms 4 projecting in front thereof. In this operation the rod 15 through nut 19 draws the rear end of strap 10 up through slot 3.

All parts above described are to be made 20 of any suitable materials, though wood is preferred by me for the seat 1 with resilient metal for all other parts, especially the clamping member or strap 10.

It is apparent that various changes may 25 be made in the construction, combination and shape of the various parts of my invention, of which only the preferred form is shown and described herein, without departing from the spirit thereof, and it is 30 my intention and desire to include all such in the appended claims.

Having thus described my invention, what I claim as new and desire to secure by Letters Patent is:

35 1. An auxiliary seat for infants provided with a folding rest mounted thereon and a clamping device adapted to engage detachably the permanent hinged seat of a water-closet below said auxiliary seat, said 40 device being connected with said folding rest and folding simultaneously therewith.

2. An auxiliary seat for infants provided with a folding rest, and a folding clamp

adapted to engage the permanent seat of a water-closet and comprising an upwardly 45 bent slotted strap pivotally connected to said auxiliary seat and a screw-threaded rod protruding through the slot in said strap and pivotally connected to said rest, and a nut on said rod bearing against said strap, 50 the screw-threaded part of said rod being bent forward.

3. An auxiliary seat for infants, a rest and arms pivotally connected to said seat and rest, in combination with a pivoted 55 strap, a clamping plate carried thereby, a rod pivotally connected to said rest and a nut turning on the end of said rod and engaging said strap.

4. An auxiliary seat for infants, a rest 60 and arms pivotally connected to said seat and said rest, in combination with a strap pivotally connected to the under face of said seat, a clamping plate carried by said strap, a rod pivotally mounted on said seat, 65 pivotally connected to said rest and having its lower end protruding through the slot in said plate, and a nut turning on the end of said rod and engaging said strap.

5. An auxiliary seat for infants, a rest 70 and arms pivotally connected thereto, in combination with a slotted strap pivotally connected to said seat, a rod pivotally mounted on said seat, pivotally connected to said rest and having its lower end protruding through the slot in said plate, and means moving on the lower end of said rod 75 and longitudinally thereof and engaging said strap to force it upward.

In testimony whereof, I have signed my 80 name to this specification in the presence of two subscribing witnesses.

FRANK H. KNIGHT.
